UNITED STATES PATENT OFFICE

151,486

DESIGN FOR A GAME BOARD

William G. Batchelder, Omaha, Nebr.

Application February 24, 1947, Serial No. 137,111

Term of patent 14 years

(Cl. D34—5)

To all whom it may concern:

Be it known that I, William G. Batchelder, a citizen of the United States, residing at Omaha, in the county of Douglas and State of Nebraska, have invented a new, original, and ornamental Design for Game Board, of which the following is a specification, reference being had to the accompanying drawing, forming part thereof.

I claim:

The ornamental design for a game board, as shown.

WILLIAM G. BATCHELDER.
